UNITED STATES PATENT OFFICE.

DAVID E. HUNTER, OF CAMBRIDGE, MASSACHUSETTS, ASSIGNOR TO
LIBRARY BUREAU, OF BOSTON, MASSACHUSETTS, A CORPORATION
OF MASSACHUSETTS.

LOCKING DEVICE FOR CARD-INDEX SYSTEMS.

SPECIFICATION forming part of Letters Patent No. 715,807, dated December 16, 1902.

Application filed November 7, 1901. Serial No. 81,450. (No model.)

To all whom it may concern:

Be it known that I, DAVID E. HUNTER, a citizen of the United States, and a resident of Cambridge, in the county of Middlesex and State of Massachusetts, have invented new and useful Improvements in Locking Devices for Card-Index Systems, of which the following is a specification.

My invention relates to card catalogue and index systems, and is especially adapted to daily-balance and ledger card systems, where-in certain selected cards, representing individual accounts, are to be differentiated from the general rank of cards in a box for temporarily calling attention to such selected cards.

Mechanically my invention consists in locking and unlocking devices for controlling the cards and for guarding against errors on the part of the persons in charge of the card system.

In the drawings hereto annexed, which illustrate an embodiment of my invention, Figure 1 is a vertical longitudinal section of a card box or drawer with my improvements embodied therein. Fig. 2 is a similar view of the front part of a drawer with my card-locking device in open or working position. Fig. 3 is a front elevation of a detail—the locking-plate which is secured to the front of the drawer or box. Fig. 4 is a transverse vertical section of a drawer or box midway of its length, showing the normal positions of the cards and my locking devices. Fig. 5 is a view similar to Fig. 4, showing my locking devices in action and a card transferred to its abnormal or prominent position. Fig. 6 is a vertical transverse section along the line 6-6, Fig. 1, of part of the drawer or box of Fig. 4, viewed from the right. Figs. 7 and 8 are detail illustrations showing different positions of my card locking and unlocking devices.

The arrangement of cards in what may be termed "normal" and "abnormal" position is illustrated in Figs. 4 and 5. In Fig. 4 the cards N are stacked one behind the other in the drawer or box, which is wider than the cards themselves. When in normal position, no card is distinguished from its

fellow, all standing against the side S of the drawer; but when it is desired to place some of the cards in abnormal position, whereby attention is called thereto, such cards are moved from the position shown in Fig. 4 to 55 the full-line position (Shown in Fig. 5.) For instance, if the card system is being used for daily-balance and ledger work each card is devoted to the account of one customer or correspondent, a new entry against a customer is placed on his card, which is withdrawn from its normal position of alinement with the other cards, Fig. 4, and this card is placed back in the drawer in the abnormal position, (shown in Fig. 5,) out of alinement 60 with the general mass of the cards in the drawer. At the close of a day all the new entries are made prominent by the position of the cards thus placed and are taken off for balance. When the day's work is completed, 70 these cards are replaced in their usual position in alinement with the general mass of cards.

My improvements render it easy to withdraw any desired card from its normal position in the stack, make it impossible to return a card inadvertently to its normal position, and provide ready means for restoring cards from abnormal to normal position when it is proper to do so. I also provide devices for holding the cards in such alinement when in normal position that there is no danger of impeding the movements of the card-releasing devices by reason of friction of the cards against the same.

The cards N are notched at the bottom at n' and n², Fig. 4. The notch n' is idle when the cards are in their normal position and serves to secure the card in abnormal position by engaging with the cleat b, Fig. 5. 75 The notch n² is peculiarly shaped, having a narrow throat or opening at the lower edge of the card and an enlargement bounded by the curve n³ and the incline n⁴, Fig. 4. The cards N are secured in their normal position 80 by means of the retaining-rod A, from which a blade a projects laterally and which is capable of a rotary or wrist movement. When a card N is pulled upward, the incline n⁴ 85 presses the blade a upward, turning the re- 90 95 100

taining-rod A to the position shown in Fig. 5, so that the narrow neck of the notch n^2 passes over the rod A as the card is lifted. When the card is withdrawn, a spring returns the 5 blade A to the position shown in Fig. 4. The card is now replaced in the drawer. The position of the retaining-rod A prevents the card from returning to its original position, so that if the person handling the card should 10 inadvertently attempt to replace it in its normal original position he will be automatically reminded of his mistake and will place the card in the full-line position. (Shown in Fig. 5.) The dotted lines, Fig. 5, show the manner 15 in which the withdrawal of a card causes the rod A to turn and release the card. When the time comes to replace all the cards in their regular alinement, the rod A is moved to its position shown in Fig. 5; but this movement calls for conscious manual action on 20 the part of the user. It is obvious that the spring which controls the wrist movement of the rod A must be quite light, because the cards themselves are called upon to actuate 25 the rod A by their dragging movement past the blade a if the cards N were held in alinement only by the rod A and impede its turning movement even to such a degree that a card withdrawn would be torn or bent in 30 the act. In order to guard against this difficulty, the cleat b, which engages with the notch n' when the cards are in their abnormal and prominent position, is so placed with 35 relation to the cards N and the sides of the receptacle which holds them that when the cards are placed in abnormal position they are held clear of the rod A, and also when they are placed in normal alinement the cards N are prevented from being displaced later- 40 ally to such an extent that the side walls of the notch n^2 touch or are rubbed by the rod A. The clearance between the cards N, side S of the receptacle, and cleat b is less than 45 the clearance of the notch n^2 on the rod A and block a. Thus the blade A when free to turn is very easily moved, and the sides of the notch n^2 suffer no damage in the act of withdrawing a card. The details of the mechanism by which these results are effected are 50 as follows:

The card-retaining rod A, Fig. 1, lies parallel with the bottom B of the drawer and is supported at its ends on pintle-bearings a^2 and a^4 , which rest and turn, respectively, in 55 the screw-plug a^3 in the back wall R of the drawer and in the central hole a^6 in the movable block a^5 at the front of the drawer. The blade a and tang a' project laterally from the retaining-rod A. The front end of the rod A 60 lies in the cylindrical cavity C', cut for the purpose in the block C, which fills the forward end of the drawer. Stops $c' c^2$, fixed in the block C, project into the cavity C' and limit the rotary or wrist movement of the rod 65 A to about one-quarter of a full turn by acting on the tang a'. A spring m, coiled around the rod A, bears against the edge c^4 of the

block C and constantly tends to turn the tang a' into contact with the stop c^2 , and thus to bring the blade a into horizontal position, 70 Fig. 4. As shown in Fig. 1, the rod A is secured in position against the action of the spring m, so that cards N, Figs. 4, 5, may be removed from or placed in their regular alinement at will. 75

The devices by which the rod A may be manually controlled, placed in normal working position or locked either in position to retain or release cards, are as follows: The cylindrical centrally - perforated block a^5 , 80 which rests in the cylindrical cavity C' of the block C, is secured by a bolt or rivet d^3 to the shaft d^2 of the operating-handle D. A leaf-spring c^3 , secured to the block C and operating in the cavity C', presses against the block a^5 and urges it constantly toward the 85 rod A. By means of the handle D and its connections the block a^5 may be slid or turned in the cavity C'. Pins $d^4 d^5$ project from the inner face of the block a^5 and overlap the tang a'. A lug d' projects from the handle-shaft d^2 just behind the flange d and coöperates with the lock-plate e, Fig. 3. The lock-plate e is secured to the front E of the drawer and has a central perforation e' , which accommodates the handle-shank d^2 . Notches $e^2 e^3 e^4$ 90 are cut at the edge of the perforation e' at ninety degrees angular distance apart and are of proper size and depth to coöperate with the lug d' . It is plain that as the handle D is turned to the right or left the pins $d^4 d^5$ will 95 alternately release the rod A, leaving it free to turn within the limits prescribed by the stops $c' c^2$ or lock the rod A either in position to release or retain the cards N, according to 100 the position of the blade a.

Fig. 6 shows the pins d^4 and d^5 in such position that the rod A is locked in position to release the cards N or permit their replacement in the regular alinement. 110

Fig. 7 shows the pins $d^4 d^5$ in such position that the rod A and its blade a may turn through a right angle, the tang a' and stops $c' c^2$ limiting the movement. In this case a card N may be withdrawn from the normal 115 position, the rod A turning to release it, and return under the stress of the spring m, so as to exclude a card from replacement in the regular alinement.

Fig. 8 shows the pins $d^4 d^5$ in position to 120 lock the rod A with its blade a in horizontal card-retaining position.

The manner in which the rod A is manually controlled is shown in Fig. 2. The handle D is pulled out until the lug d' is clear of the lock-plate e. Then the handle D and the parts connected therewith may be turned until the lug d' registers with another notch—say e^3 —in the lock-plate. The spring c^3 automatically returns the handle D to position 125 with the flange d against the face of the plate e.

What I claim, and desire to secure by Letters Patent, is—

1. In an index-card system, the combination of a card-receptacle, cards retained in stack alignment in the receptacle by a yielding retaining-bar, notches in the cards which engage the retaining-bar, the retaining-bar, movable from normal card-retaining position to abnormal card-releasing position, means for automatically returning the retaining-bar to card-retaining position, the said notches in the cards being so shaped as to move the retaining-bar to card-releasing position as a card is withdrawn from the stack, and so as to slip over the said bar when it is so moved to card-releasing position, the notch-entrance being so shaped that the retaining-bar will not enter therein when it is in normal card-retaining position, and movable devices, manually controllable whereby the said retaining-bar may be positively held either in card-releasing or card-retaining position, substantially as described.
2. In an index-card system, the combination of a card-receptacle, cards retained in stack alignment in the receptacle by a yielding retaining-bar, notches in the cards which engage the retaining-bar, the retaining-bar, movable from normal card-retaining position to abnormal card-releasing position, means for automatically returning the retaining-bar to card-retaining position, stops, fixed in the card-receptacle whereby the movement of the retaining-bar is limited, the said notches in the cards being so shaped as to move the retaining-bar to card-releasing position as a card is withdrawn from the stack, and so as to slip over the said bar when it is so moved to card-releasing position, the notch-entrance being so shaped that the retaining-bar will not enter therein when it is in normal card-retaining position, and movable devices, manually controllable whereby the said retaining-bar may be positively held either in card-releasing or card-retaining position, substantially as described.
3. In an index-card system, the combination of a card-receptacle, cards retained in stack alignment in the receptacle by a yielding retaining-bar, the said bar pivoted and provided with a laterally-projecting blade, notches in the cards which engage said blade, the retaining-bar movable on its pivots from normal card-retaining position to abnormal card-releasing position, means for automatically turning the bar to card-retaining position, the said notches in the cards being so shaped as to turn the retaining-bar to card-releasing position as a card is withdrawn from the stack and so as to slip over the blade when it is so moved to card-releasing position, the notch-entrance being so shaped that the blade will not enter therein when it is in normal card-retaining position, and stops, fixed in the card-receptacle whereby the turning movement of the retaining-bar is limited, and manually-controllable movable pins whereby the retaining-bar may be positively held in

either card-releasing or card-retaining position.

4. In an index-card system, the combination of cards, notched to engage a movable retaining-bar, the retaining-bar, pivotally mounted, a blade on the bar, a spring to return the bar to normal card-retaining positions, manually-controllable devices comprising stop-pins, a handle for operating the same, and locking contrivances, whereby the movable retaining-bar may at will be positively retained in card-releasing or card-retaining position, or be left free to move in response to the withdrawal of a card therefrom, substantially as described.

5. In an index-card system, the combination of cards notched to engage a movable retaining-bar, the retaining-bar, pivotally mounted, a blade on the bar, a spring to return the bar to normal card-retaining positions, stops, fixed in the card-receptacle, whereby the movement of the retaining-bar is limited, manually-controllable devices comprising stop-pins, a handle for operating the same, and locking contrivances, whereby the movable retaining-bar may at will be positively retained in card-releasing or card-retaining position, or be left free to move in response to the withdrawal of a card therefrom, substantially as described.

6. In an index-card system, the combination of a card-receptacle, a movable card-retaining bar, pivotally mounted, a tang on the bar and fixed stops engaging therewith, movable stop-pins, connected to a handle, the handle mounted to slide and turn, the said stop-pins capable of engagement with the retaining-bar tang, a locking-plate coöperating with the said handle in such manner that sliding movement of the handle controls the locking devices, and turning movement of the handle controls the stop-pins, substantially as described.

7. In an index-card system, the combination of a card-receptacle, a movable card-retaining bar, pivotally mounted, a tang on the bar, fixed stops engaging therewith, movable stop-pins, connected to a handle, the handle mounted to slide and turn, the said stop-pins capable of engagement with the retaining-bar tang, a locking-plate coöperating with the said handle in such manner that sliding movement of the handle controls the locking devices, and turning movement of the handle controls the stop-pins, and a spring constantly urging the said handle into locked position, substantially as described.

8. In an index-card system the combination of a card-receptacle, cards of less width than the receptacle, retained in stack alignment by a yielding retaining-bar, notches in the cards which engage the retaining-bar, the retaining-bar movable from normal card-retaining position to abnormal card-releasing position, means for automatically returning the retaining-bar to card-retaining position,

the said notches in the cards being shaped so as to move the retaining-bar to card-releasing position as a card is withdrawn from the stack, and so as to slip over the said bar 5 when it is so moved to card-releasing position, the notch-entrance being so shaped that the retaining-bar will not enter therein when the bar is in normal card-retaining position, a spacing-cleat secured to the card-receptacle, whereby the cards are registered with the retaining-bar when in normal alinement, and notches in the cards adapted to engage with the spacing-cleat when the cards are in abnormal position, substantially as described.

15 9. In an index-card system, the combination of a card-receptacle, cards retained in stack alignment in the receptacle by a yielding retaining-bar, notches in the cards which engage the retaining-bar, the retaining-bar, movable from normal card-retaining position to abnormal card-releasing position, means for automatically returning the retaining-bar to card-retaining position, the said notches in the cards being so shaped as to move the retaining-bar to card-releasing position as a card is withdrawn from the stack, and so as to slip over the said bar when it is so moved to card-releasing position, the notch-entrance being so shaped that the retaining-bar will not enter therein when it is in normal card-retaining position, and movable devices, manually controllable whereby the said retaining-bar may be positively held either in card-releasing or card-retaining position, and

30 35 a spacing-cleat secured to the card-receptacle, and notches in the cards to engage said cleat, whereby the cards are registered with the retaining-bar, substantially as described.

10. In an index-card system, the combination of a card-receptacle, cards retained in stack alinement in the receptacle by a yielding retaining-bar, notches in the cards which engage the retaining-bar, the retaining-bar, movable from normal card-retaining position to abnormal card-releasing position, means for automatically returning the retaining-bar to card-retaining position, the said notches in the cards being so shaped as to move the retaining-bar to card-releasing position as a 45 card is withdrawn from the stack, and so as to slip over the said bar when it is so moved to card-releasing position, the notch-entrance being so shaped that the retaining-bar will not enter therein when it is in normal card- 50 retaining position, and movable devices, manually controllable whereby the said retaining-bar may be positively held either in card-releasing or card-retaining position, a spacing-cleat secured to the card-receptacle, 55 whereby the cards are registered with the retaining-bar when in normal alinement, and notches in the cards adapted to engage with the spacing-cleat when the cards are in abnormal position, substantially as described.

65 11. In an index-card system, the combination of a card-receptacle, cards retained in stack alignment in the receptacle by a yield-

ing retaining-bar, notches in the cards which engage the retaining-bar, the retaining-bar, movable from normal card-retaining position to abnormal card-releasing position, means for automatically returning the retaining-bar to card-retaining position, stops, fixed in the card-receptacle whereby the movement of the retaining-bar is limited, the said notches in the cards being so shaped as to move the retaining-bar to card-releasing position as a card is withdrawn from the stack, and so as to slip over the said bar when it is so moved to card-releasing position, the notch-entrance being so shaped that the retaining-bar will not enter therein when it is in normal card-retaining position, and movable devices, manually controllable whereby the said retaining-bar may be positively held either in card-releasing or card-retaining position, and a spacing-cleat secured to the card-receptacle, and notches in the cards to engage said cleat, whereby the cards are registered with the said retaining-bar, substantially as described. 90

12. In an index-card system, the combination of a card-receptacle, cards retained in stack alignment in the receptacle by a yielding retaining-bar, notches in the cards which engage the retaining-bar, the retaining-bar, 95
movable from normal card-retaining position to abnormal card-releasing position, means for automatically returning the retaining-bar to card-retaining position, stops, fixed in the card-receptacle whereby the movement of the retaining-bar is limited, the said notches in the cards being so shaped as to move the retaining-bar to card-releasing position as a card is withdrawn from the stack, and so as to slip over the said bar when it is so moved to card-releasing position, the notch-entrance being so shaped that the retaining-bar will not enter therein when it is in normal card-retaining position, and movable devices, manually controllable whereby the said retaining-bar may be positively held either in card-releasing or card-retaining position, a spacing-cleat secured to the card-receptacle, whereby the cards are registered with the retaining-bar when in normal alignment, and notches in the cards adapted to engage with the spacing-cleat when the cards are in abnormal position, substantially as described. 100 105 110 115

13. In an index-card system, the combination of a card-receptacle, cards retained in stack alignment in the receptacle by a yielding retaining-bar, the said bar pivoted and provided with a laterally-projecting blade, notches in the cards which engage said blade, the retaining-bar movable on its pivots from normal card-retaining position to abnormal card-releasing position, means for automatically turning the bar to card-retaining position, the said notches in the cards being so shaped as to turn the retaining-bar to card-releasing position as a card is withdrawn from the stack and so as to slip over the blade when it is so moved to card-releasing position, the notch-entrance being so shaped that the

blade will not enter therein when it is in normal card-retaining position, and stops, fixed in the card-receptacle whereby the turning movement of the retaining-bar is limited, and 5 a spacing-cleat secured to the card-receptacle, whereby the cards are registered with the said retaining-bar, substantially as described.

14. In an index-card system, the combination of a card-receptacle, cards retained in 10 stack alinement in the receptacle by a yielding retaining-bar, the said bar pivoted and provided with a laterally-projecting blade, notches in the cards which engage said blade, the retaining-bar movable on its pivots from 15 normal card-retaining position to abnormal card-releasing position, means for automatically turning the bar to card-retaining position, the said notches in the cards being so shaped as to turn the retaining-bar to card-releasing position as a card is withdrawn from the stack and so as to slip over the blade when it is so moved to card-releasing position, the notch-entrance being so shaped that the blade will not enter therein when it is in normal 20 card-retaining position, and stops, fixed in the card-receptacle whereby the turning movement of the retaining-bar is limited, a spacing-cleat secured to the card-receptacle, whereby the cards are registered with the retaining-bar when in normal alinement, and notches in the cards adapted to engage with the spacing-cleat when the cards are in abnormal position. 25

15. In an index-card system, the combination of a card-receptacle, cards retained in 30 stack alinement in the receptacle by a yielding retaining-bar, the said bar pivoted and provided with a laterally-projecting blade, notches in the cards which engage said blade, the retaining-bar movable on its pivots from 35 normal card-retaining position to abnormal card-releasing position, means for automatically turning the bar to card-retaining position, the said notches in the cards being so shaped as to turn the retaining-bar to card-releasing position as a card is withdrawn from the stack and so as to slip over the blade when it is so moved to card-releasing position, the notch-entrance being so shaped that the blade will not enter therein when it is in normal 40 card-retaining position, and stops, fixed in the card-receptacle whereby the turning movement of the retaining-bar is limited, a spacing-cleat secured to the card-receptacle, whereby the cards are registered with the retaining-bar when in normal alinement, and notches in the cards adapted to engage with the spacing-cleat when the cards are in abnormal position, substantially as described. 45

16. In an index-card system, the combination of a card-receptacle, cards retained in 50 stack alinement in the receptacle by a yielding retaining-bar, the said bar pivoted and provided with a laterally-projecting blade, notches in the cards which engage said blade, the retaining-bar movable on its pivots from 55

normal card-retaining position to abnormal card-releasing position, means for automatically turning the bar to card-retaining position, the said notches in the cards being so shaped as to turn the retaining-bar to card-releasing position as a card is withdrawn from the stack and so as to slip over the blade when it is so moved to card-releasing position, the notch-entrance being so shaped that the blade will not enter therein when it is in normal card-retaining position, and stops, fixed in the card-receptacle whereby the turning movement of the retaining-bar is limited, and manually-controllable movable pins whereby the retaining-bar may be positively held in either card-releasing or card-retaining position, a spacing-cleat secured to the card-receptacle, whereby the cards are registered with the retaining-bar when in normal alinement, and notches in the cards adapted to engage with the spacing-cleat when the cards are in abnormal position. 70

17. In an index-card system, the combination of cards, notched to engage a movable retaining-bar, the retaining-bar, pivotally mounted, a blade on the bar, a spring to return the bar to normal card-retaining position, manually-controllable devices comprising stop-pins, a handle for operating the same, and locking contrivances, whereby the movable retaining-bar may at will be positively retained in card-releasing or card-retaining position, or be left free to move in response to the withdrawal of a card therefrom, a spacing-cleat secured to the card-receptacle, whereby the cards are registered with the retaining-bar when in normal alinement, and notches in the cards adapted to engage with the spacing-cleat when the cards are in abnormal position, substantially as described. 90

18. In an index-card system, the combination of cards, notched to engage a movable retaining-bar, the retaining-bar, pivotally mounted, a blade on the bar, a spring to return the bar to normal card-retaining position, stops, fixed in the card-receptacle, whereby the movement of the retaining-bar is limited, manually-controllable devices comprising stop-pins, a handle for operating the same, and locking contrivances, whereby the movable retaining-bar may at will be positively retained in card-releasing or card-retaining position, or be left free to move in response to the withdrawal of a card therefrom, a spacing-cleat secured to the card-receptacle, whereby the cards are registered with the retaining-bar when in normal alinement, and notches in the cards adapted to engage with the spacing-cleat when the cards are in abnormal position, substantially as described. 110

19. In an index-card system, the combination of a card-receptacle, a movable card-retaining bar, pivotally mounted, a tang on the bar and fixed stops engaging therewith, movable stop-pins, connected to a handle mounted to slide and turn, the said stop-pins capa- 115

ble of engagement with the retaining-bar tang, a locking-plate coöperating with the said handle in such manner that sliding movement of the handle controls the locking devices, and turning movement of the handle controls the stop-pins, a spacing-cleat secured to the card-receptacle, whereby the cards are registered with the retaining-bar when in normal alinement, and notches in the cards 10 adapted to engage with the spacing-cleat when the cards are in abnormal position, substantially as described.

20. In an index-card system, the combination of a card-receptacle, a movable card-retaining bar, pivotally mounted, a tang on the bar and fixed stops engaging therewith, movable stop-pins, connected to a handle mounted to slide and turn, the said stop-pins capable of engagement with the retaining-bar tang,

a locking-plate coöperating with the said handle in such manner that sliding movement of the handle controls the locking devices, and turning movement of the handle controls the stop-pins, and a spring constantly urging the said handle into locked position, a spacing-cleat secured to the card-receptacle, whereby the cards are registered with the retaining-bar when in normal alinement, and notches in the cards 25 adapted to engage with the spacing-cleat when the cards are in abnormal position, substantially as described.

Signed by me at Boston, Massachusetts, this 25th day of October, 1901.

DAVID E. HUNTER.
